(57) **CLAIM**

The ornamental design for an “operation interface,” as shown and described.

DESCRIPTION

The patent or application file contains at least one drawing executed in color. Copies of this patent or patent application

publication with color drawing(s) will be provided by the Office upon request and payment of the necessary fee.

FIG. 1 is a front view of an operation interface.

FIG. 2 is a left-side view of the operation interface of FIG. 1.

FIG. 3 is a top view of the operation interface of FIG. 1.

FIG. 4 is a front perspective view of the operation interface of FIG. 1.

FIG. 5 is a rear perspective view of the operation interface of FIG. 1.

FIG. 6 is a right-side view of the operation interface of FIG. 1.

FIG. 7 is a rear side view of the operation interface of FIG. 1.

FIG. 8 is a bottom view of the operation interface of FIG. 1.

FIG. 9 is a front view of a second example of the operation interface.

FIG. 10 is a right-side view of the operation interface of FIG. 9.

FIG. 11 is a top view of the operation interface of FIG. 9.

FIG. 12 is a front perspective view of the operation interface of FIG. 9.

FIG. 13 is a second front perspective view of the operation interface of FIG. 9.

FIG. 14 is a rear perspective view of the operation interface of FIG. 9.

FIG. 15 is a left-side view of the operation interface of FIG. 9.

FIG. 16 is a rear side view of the operation interface of FIG. 9.

FIG. 17 is a bottom view of the operation interface of FIG. 9; and,

FIG. 18 is a front perspective view of an operation interface that is the same as the operation interface of FIG. 4 but the operation interface of FIG. 18 is executed in color.

While FIGS. 1-18 include solid lines, it is the Applicant's intention to disclose all of the features of FIGS. 1-18 as part of the specification and to reserve the right to claim any or all of those features in any combination in this or a continuing application by converting any one or more solid lines of FIGS. 1-18 into broken lines in order to claim any aspect(s) of this disclosed design in isolation or in any combination. The Applicant's disclosure is, thus, not limited

(Continued)

to the claim reflected in FIGS. 1-18 but encompasses every aspect of FIGS. 1-18 alone and/or in combination. The broken lines in the drawings depict unclaimed environmental subject matter. The features shown in broken lines form no part of the claimed design.
